(57) **CLAIM**

The ornamental design for an animal chew, as shown and described.

DESCRIPTION

FIG. 1 is an isometric top, right side and end view of an animal chew, showing my new design;

FIG. 2 is a top plan view thereof;

FIG. 3 is a bottom plan view thereof;

FIG. 4 is a side view, the opposite side view being the same image thereof; and,

FIG. 5 is an end view, the opposite end view being the same image thereof.
